UNITED STATES PATENT OFFICE.

WALTER A. PERRY, OF NEW BEDFORD, MASSACHUSETTS.

DESIGN FOR A HOOK FOR ROPES.

SPECIFICATION forming part of Design No. 22,293, dated March 14, 1893.

Application filed October 27, 1892. Serial No. 450,188. Term of patent 7 years.

To all whom it may concern:

Be it known that I, WALTER A. PERRY, a citizen of the United States of America, residing at New Bedford, in the county of Bristol and State of Massachusetts, have invented and produced an original Design for Hooks or Fastening Devices for Lines or Ropes, of which the following is a specification, reference being had to the accompanying drawing, forming part thereof, and in which—

The figure is a perspective view of my design.

The leading features of my design consist of a base plate with a projecting portion or shank at the end of which are formed three projecting arms, the upper arms being tapered and beveled to provide double wedge-shaped spaces between them, or, in other words, spaces which taper vertically and transversely, and the depending pin which is tapered as shown.

A designates the base or support upon which

is formed a projecting portion or shank A', which is bent and provided at its outer end with three upwardly projecting arms B, B' and B'', the outer arms being located to one side of the shank so as to provide shoulders c c. Between these shoulders and immediately below the central arm B' depends a pin d which tapers throughout its length.

From the foregoing it will be seen that the essential part of my design is the shank A' having the upwardly projecting arms and a single depending arm.

I claim—

The design for a hook substantially as shown and described.

In testimony whereof I affix my signature in presence of two witnesses.

WALTER A. PERRY.
